US0D1073771S

(12) **United States Design Patent** (10) **Patent No.:** **US D1,073,771 S**
(45) **Date of Patent:** **** May 6, 2025**

(54) **CAMERA MOUNT**

(71) Applicant: **Amazon Technologies, Inc.**, Seattle, WA (US)

(72) Inventors: **Alexsandra M. Bowers**, Fairview Park, OH (US); **Paul Douglas Grearson**, Andover, MA (US); **Ryan David Hruska**, North Royalton, OH (US); **James Siminoff**, Pacific Palisades, CA (US); **Youssef Takhchi**, Cleveland, OH (US); **Treasure Hinds**, Seattle, WA (US); **Greg Janky**, Seattle, WA (US); **Alexandra Specht**, Medford, MA (US)

(73) Assignee: **AMAZON TECHNOLOGIES, INC.**, Seattle, WA (US)

(**) Term: **15 Years**

(21) Appl. No.: **29/909,139**

(22) Filed: **Aug. 1, 2023**

(57) **CLAIM**

The ornamental design for a camera mount, as shown and described.

DESCRIPTION

FIG. 1 is a top, front, right-side perspective view of a camera mount;
FIG. 2 is a bottom, back, left-side perspective view thereof;
FIG. 3 is a front view thereof;
FIG. 4 is a back view thereof;
FIG. 5 is a left-side view thereof;
FIG. 6 is a right-side view thereof;
FIG. 7 is a top view thereof;
FIG. 8 is a bottom view thereof; and,
FIG. 9 is a top, front, right-side perspective view thereof. The dashed broken lines in the figures depict portions of the camera mount that form no part of the claimed design. The additional dashed broken lines seen only in FIG. 9 depict environment and form no part of the claimed design. The dot-dashed broken lines represent boundaries of the claimed camera mount and form no part of the claimed design.

1 Claim, 9 Drawing Sheets
